Inventor:
Elmer G. Daniels.
By *Fred J. Harms*
Attorney.

UNITED STATES PATENT OFFICE.

ELMER G. DANIELS, OF ST. LOUIS, MISSOURI.

PNEUMATIC MATTRESS.

Application filed June 20, 1924. Serial No. 721,363.

To all whom it may concern:

Be it known that I, ELMER G. DANIELS, a citizen of the United States, residing in the city of St. Louis and State of Missouri, 5 have invented certain new and useful Improvements in Pneumatic Mattresses, of which the following is a specification.

This invention relates to new and useful improvements in pneumatic mattresses, and, 10 has for its object to provide a comfortable mattress which is a distinct and practical improvement to overcome certain practical objections to, and defects in, mattress structures adapted to be filled with air.

15 A further object of the invention is the provision of a mattress structure, which is simple in construction, inexpensive in manufacture and highly efficient for the purpose intended.

20 With the above and other objects in view, the invention consists in the novel features of construction, arrangement and combination of parts hereinafter described and finally pointed out in the claims hereto appended.

25 Referring to the accompanying drawings forming a part of this specification, wherein like characters of reference denote similar parts throughout the several views:

30 Fig. 1, is a view in perspective of a mattress constructed in accordance with my invention.

35 Fig. 2, is a view in perspective of the mattress with one end of the inflatable core and the casing broken away.

40 In carrying out the aim of my invention, I employ a suitable fabric mattress casing, or covering designated 1. This casing may be of any desired shape, length, width and thickness, as is manifest, and is provided with the upper casing section 2, the lower casing section 3, the end casing sections 4 and the side casing sections 5.

45 A suitable endless wire frame member 6 is disposed within the casing 1 and engages the edges of the top casing section 2 and the upper edges of the end and side casing sections 4 and 5 and it is sewed thereto by means of suitable stitches 7 so as to prevent displacement of the frame member and provide a stiff and reinforced upper edge for the mattress. A like wire frame member 7 is also disposed within the casing 1 and engages the edges of the casing section 3 and the lower edges of the end and side casing sections 4 and 5 and the frame

member is sewed thereto by means of suitable stitches 8 to prevent displacement of the frame member and to provide a stiff and reinforced lower edge for the mattress. 60

The side members of each frame member 6 and 7 are tied together by means of suitable wire connections 9 and 10, respectively, or their equivalent, such for instance as a wire netting so as to prevent lateral bulging 65 of the mattress frames under weight of pressure.

The bottom casing section 3 of the mattress casing is slit centrally and longitudinally, as at 11 and the opposed edges of the slit are preferably faced upon both sides of the casing section 3 by means of folder fabric strips 12. These fabric strips 12 are each provided with a plurality of openings 13 for receiving a suitable tie string or cord 14 for 70 lacing purposes to close the opening formed by the slit 11.

A suitable inflatable soft rubber tube or casing 15 is positioned or disposed within the fabric casing 1 and is of a configuration 80 to correspond to the interior configuration of the fabric casing 1. The rubber tube or casing 15 is positioned within the fabric casing 1 through the slit 11 in the bottom section 3 thereof when it is unlaced and it is 85 held in position by lacing the string 14 as shown in Fig. 1. The tube 15 is provided with a suitable valve stem 16 which is provided with air valve 17 so that the inner rubber tube or casing 15 may be inflated to 90 the proper pressure to provide a comfortable mattress. When the mattress tube 15 is deflated, it is evident that the outer fabric casing 1 will collapse and the mattress may be folded or rolled up into a small package 95 for storage or transportation.

It is evident that a mattress constructed in accordance with the foregoing description will be light, strong, durable, comfortable and sanitary and highly efficient for the 100 purpose intended.

The many advantages of the herein described invention will readily suggest themselves to those skilled in the art to which it appertains. 105

I do not wish to be understood as having limited myself to the exact details of construction shown and described, but desire to have it understood that the invention I have shown in the drawings is merely illustrative, as it is manifest that various minor changes may be made in the exact construc- 110

tion and particular arrangement of parts without departing from the spirit of my invention, hence I reserve the right to make any such changes, or modifications as may 5 fairly fall within the scope of the appended claims when fairly construed.

What I claim is:

1. In a mattress structure, an air inflated elastic receptacle, a fabric casing for said 10 elastic receptacle, a slit formed in the fabric casing, facing strips having openings therein for the side edges of said slit, a lacing string receivable in said opening for closing the slit, and a pair of opposed end- 15 less wire frame members disposed within the fabric casing and sewed thereto by means of stitches for reinforcing the upper and lower edges of the fabric casing.

2. In a mattress structure, an air inflated elastic receptacle, a fabric casing for said 20 elastic receptacle, a slit formed in the fabric casing, facing strips having openings therein for the side edges of said slit, a lacing string receivable in said opening for closing the slit, a pair of opposed endless 25 wire frame members disposed within the fabric casing and sewed to the upper and lower edges thereof by means of stitches for reinforcing the edges of the mattress and means for connecting the side members of 30 the endless frame members to prevent lateral bulging thereof when weight is applied upon the mattress.

In testimony whereof, I have hereunto signed my name to the specification.

ELMER G. DANIELS.
